UNITED STATES PATENT OFFICE.

FRANK TAYLOR, OF ROCHESTER, NEW YORK.

DESIGN FOR A SCALE.

SPECIFICATION forming part of Design No. 30,987, dated June 13, 1899.

Application filed January 30, 1899. Serial No. 703,906. Term of patent 7 years.

To all whom it may concern:

Be it known that I, FRANK TAYLOR, a citizen of the United States, and a resident of Rochester, in the county of Monroe and State 5 of New York, have invented and produced a certain new and original Design for a Scale, of which the following is a specification.

This invention relates to a design for a scale for thermometers and other measuring instruments; and it consists in the new and original scale, substantially as herein shown and described.

In the drawings, A A are parallel lines of substantially equal length, indicating the 15 greater graduations, and B B are sets of equal numbers of equidistant parallel lines parallel to and between each pair of adjacent lines A A. The lines B B, indicating the smaller graduations, are arranged in sets alternating 20 on the two sides of the middle vertical line of the scale. In other words, between any two

adjacent lines A A, indicating a greater graduation, is a set of parallel lines B B, indicating the smaller graduations, extending outward in one direction from the middle vertical line of the scale, and between the lines A A, representing the greater graduation next to the one just mentioned, is another set of parallel lines B B, which extends outward from said middle vertical line and in the opposite direction from the set of lines B B just mentioned. 25

The leading feature of this design consists in the scale having upon it a graduation pattern consisting of the lines A A and B B. 30

What I claim is—

The design for a scale herein shown and described.

FRANK TAYLOR.
